SHADE PULL

Romulus Saccoccio, Providence, R.I., assignor to Industrial Foundry Mills, Inc., Providence, R.I., a corporation of Rhode Island

Filed Oct. 2, 1963, Ser. No. 76,840

Term of patent 14 years

(Cl. D21—1)

FIG. 1

FIG. 2

FIG. 4

FIG. 3

FIG. 5

FIG. 1 is a front elevational view of a shade pull embodying my new design;

FIG. 2 is a side elevational view;

FIG. 3 is a top plan view with a portion of the screw being omitted for convenience of illustration;

FIG. 4 is an enlarged front elevational view of the screw plate portion of the pull; and

FIG. 5 is an enlarged fragmentary front elevational view of the pull element.

The dominant features of my design reside in the portions shown in full lines.

I claim:

The ornamental design for a shade pull, as shown and described.
